WEB CUTTING MECHANISM FOR
PRINTING MACHINES

Adolph M. Zuckerman, New York, N. Y., assignor
to R. Hoe & Co., Inc., New York, N. Y., a corporation of New York; Irving Trust Company, permanent trustee

Application April 20, 1932, Serial No. 606,387

16 Claims. (Cl. 270—32)

This invention relates to improvements in mechanism for cutting printed webs as they are running from a rotary printing machine and is particularly applicable to products such as magazines, pamphlets, catalogues and booklets, all of which should be produced quickly and economically, and to this end the machine should operate at full speed.

Heretofore it has only been possible to cut the running webs into uniform lengths which have been customarily equal to the circumference of the form cylinder or of such uniform lengths that the circumference of the form cylinder is a multiple thereof.

It is one of the objects of this invention to so proportion and arrange the cutting cylinders, their knives and other mechanism, that sheets of various and different lengths can be cut from a running web.

This invention enables two entirely different and independent magazines, or similar products, of dissimilar page sizes, to be printed at one time on the form cylinders, and each of their webs cut successively into sheets or signatures of differing lengths proper for each product.

In order to properly accomplish this it should be understood that the forms for each different magazine or signature are grouped successively around the form cylinder. By reason of this construction, one machine can substantially simultaneously supply sheets of dissimilar sizes for different magazines and can thus do the work which formerly required a plurality of machines, and this is a valuable feature as will be readily understood.

It is also an object of this invention to provide web cutting and folding means adapted to furnish, during the same run, sheets of different sizes, the mechanism for which is of generally improved construction, simple, durable, and inexpensive, as well as convenient, practical, serviceable and efficient in use.

With the foregoing and other objects in view, which will appear as the description proceeds, the invention resides in the combination and arrangement of parts, and in the details of construction hereinafter described and claimed, it being understood that various changes in the precise embodiment of the invention herein disclosed may be made within the scope of what is claimed without departing from the spirit of the invention.

The preferred embodiment of the invention is illustrated in the accompanying drawings wherein:

55 Figure 1 is a diagrammatic elevation looking

at the ends of the cutting cylinders in the direction of their axes:

Figure 2 is a diagrammatic elevation at right angles to the view of Figure 1 looking in the direction of the arrow 2;

Figure 3 is a more detailed end elevation of a pair of cutting cylinders with their knives and other mechanism in position to alternately cut sheets of different lengths, and

Figure 4 is a view similar to Figure 3 but with the knives positioned to successively cut sheets of the same lengths.

By means of this invention, a running web can be successively cut into sheets of different lengths as hereinbefore mentioned but for convenience of illustration the cutting cylinders are shown as arranged for only two lengths.

The cutting cylinders may be made of diameters proportional to that of the form cylinders, and by arranging the severing means thereon at different locations, various lengths of sheets and combinations thereof can be cut from a running web, as will be readily understood by one skilled in this art.

Referring now to the characters of reference on the drawings:

The mechanism is provided with a main frame indicated as 11, which as viewed in Figure 1 is on the far side and in this view the corresponding main frame 12 is removed from the front side for the sake of clearness of illustration. Another frame 13 is provided which may be independent or secured to the frames 11 and 12 as preferred.

A wide web W is forwarded in the direction of the arrow and is slit by the rotary shears 15 and their co-operating roll 14 into four narrower webs or ribbons each indicated as W'.

Turner bars 16 are provided which turn the webs or ribbons W' into face relation and they thence pass around the various guide rollers 17, 18, 19, 20 and 21, after which they are closely associated by the nipping and propelling rollers 22 and 23.

The associated webs W' thence pass between a pair of cutting cylinders; the one on the right hand side of Figure 1 is indicated as 24 and its companion cutting cylinder is indicated as 31. The cutting cylinder 24 is mounted on the shaft 25 and is adapted to be rotated about its axis and is geared to the other cutting cylinder 31 and thus arranged to move synchronously therewith so that the knives and cutting abutments will register properly to sever the ribbons W'.

The cutting cylinder 24 is provided with a knife 26 which is mounted in the usual cutter holder

in the form of cheek blocks secured in the recess 27. Another recess 28 is provided in which the knife 26 may be mounted to cut sheets of other lengths than those of the arrangement just mentioned and illustrated in Figure 3.

- The cutting cylinder 24 is also provided with the usual cutting abutment 29 and the customary impaling or collecting pins 30 which are operated in the usual manner by a rocker arm and cams. 5
10 The other companion cutting cylinder 31 is rotatably secured on the shaft 32 and, as shown in Figure 3, is similarly provided with a knife 33 mounted in the recess 34, while another recess 35 is provided to receive it when the arrangement 15 shown in Figure 4 is desired.

This cutting cylinder 31 also has the customary cutting abutment 36 and impaling pins 37, similar to those on cylinder 24, all of which operate in the usual manner to assist in severing the web 20 and to carry the cut sheets or signatures to the forwarding rolls 38 and 39 which assist in further advancing them.

As shown in Figures 1 and 2 the short sheets or signatures cut by this invention are indicated as 25 41 and the long ones are indicated as 40, while in Figure 4 these severed portions one of which is indicated as E and the next one which will follow the path indicated by the broken line E' are all of the same length, by reason of the equally 30 spaced arrangement of the cutters on the cutting cylinders as illustrated in this last named figure.

As illustrated in Figure 3 the longer cut sheet is indicated as 40 and the path of the next sheet 41 is indicated, by the broken line 41'. Feed 35 roller 42 and a co-operating drop roller 43 are shown in Figure 1 which aid in the delivery of the longer sheets or signatures 40 to the chopper blade folder having a blade 46 adapted to tuck these between the folding rollers 47 which fold 40 them longitudinally and deliver them to the packer box 48.

After passing between the forwarding roll 38 and the cutting cylinder 24 the shorter sheets or signatures 41 are advanced by the feed roller 44 45 and its companion drop roller 45 to a similar chopper blade folder provided with the blade 49 and folding rollers 50 which complete the longitudinal folds and deliver the sheets to the packer box 51, which, as illustrated, is so adjusted as to 50 provide a smaller space in order to receive and support a plurality of such shorter sheets in position as indicated in the drawings.

As shown in Figure 3 the cutting cylinders 26 and 31 have their knives and cutting abutments 55 closer together when measured circumferentially on one side of the center and further apart on the other side. This adapts them to alternately cut sheets of different lengths and in the case illustrated in Figure 3, one shorter sheet may be 60 three pages long and the next sheet will be four signatures in length, as the cutters are so spaced in this view as to produce such, although other spacing may be used.

The arrangement of cutters shown in Figure 4 65 will, however, produce sheets of equal lengths as will be readily understood.

It has only been possible with prior machines to sever the running web into sheets or signatures of uniform lengths, whereas by means of this invention a machine can still do this and in addition it can also alternately cut a running web into sheets of different lengths, and, in order to make such use more universal, either the page length or width can be disposed longitudinally of 70 the sheet. This therefore permits the simul- 75

taneous production on one machine of two magazines of different sizes.

In order to properly accomplish this it is essential to make the sum of the lengths of the shorter and longer sheets equal to the length of the circumference of the cutting cylinders.

In order that this may be fully understood the following example will be given:

A number of sixteen page sheets or signatures are required of two sizes, one of nine by thirteen 10 inches, and the other nine by eleven inches, to be printed on a rotary press with form cylinders forty-eight inches in circumference on the printing faces of the type or plates. The web is seventy-two inches wide and this is slit into four 15 ribbons each eighteen inches wide. These ribbons are forwarded, juxtaposed and cut alternately by cutting cylinders of about twenty-four inches in circumference, into sheets or signatures eleven and thirteen inches long respectively. 20

These sheets are thence forwarded alternately to two different folding mechanisms which double or fold them longitudinally to make the signatures nine inches in width, after which those of each length are delivered to a separate packer 25 box adapted to neatly and compactly contain them.

A résumé of the operation of this invention will be of interest as follows:

A wide web W is forwarded between the slit- 30 ting roll 15 and the co-operative roll 14 and is thereby slit into four ribbons as shown, each of which is indicated as W'. These ribbons are advanced and directed by the guide or feed rollers 17, 18, 19, 20 and 21 and are then jux- 35 taposed as they pass between the nipping or propelling rollers 22 and 23.

The associated ribbons are then advanced into the bite of the cutting cylinders 24 and 31 which are rotated in timed relation. As illustrated in 40 Figure 3 the knife 33 severs them in co-operation with the cutting abutment 29 and the continuation of the movement brings the knife 28 opposite the cutting abutment 36 whereby a short sheet or signature 41 is severed. As the opera- 45 tion continues the web is next severed by the knife 33 and its cutting abutment 29 thus producing a long sheet or signature 40 as the circumferential distance between the knife 33 and the cutting abutment 36 as measured around 50 the lower portion of the cylinder 31 is greater than the upper arc between them as illustrated in Figure 3. This, therefore, alternately produces long and short signatures.

As the operation continues the forward mar- 55 gins of each sheet or signature are impaled upon the collecting pins 30 or 37 as the case may be, and are thence led around their respective cylinders and are alternately delivered to the right and left, that is, the short lengths are de- 60 livered to the right between the cutting cylinder 24 and the forwarding roll 38 while the longer sheets or signatures are delivered to the left be- 65 tween the cutting cylinder 31 and the forward- ing roll 38.

Referring now to the shorter signatures, these are further advanced by the driven feed roller 44 in co-operation with the drop roller 45 and pass thence between the chopper folder blade 49 and a pair of folding rolls 50. The revolution 70 of the folder blade 49 tucks the cut webb or sheet 41 centrally and longitudinally between the pair of folding rolls 50 and it is thence delivered into the packer box 51 which is arranged to receive a group of the shorter folded sheets and hold 75

them neatly and compactly for further assembly or treatment in order to make a completed magazine or pamphlet.

While the illustration and descriptions herein relate to a longitudinal chopper blade folder it should be understood that any other form of folding or other mechanism therefor may be used for further operation after the cutting is accomplished.

10 This invention will enable a machine to produce, during the same interval of time, magazines or equivalents of two different sizes, which thus conduces to economy and facility of operation.

The machine can also produce cut sheets 15 which are all of the same lengths, so that by means of this invention it is capable of dual uses.

What I claim is:

1. In a mechanism for cutting a running web, means for severing it, in transit, into sheets of 20 unequal lengths and full width of the web engaged by the said severing means, and means for forwarding the cut sheets of each length directly from the severing means to a different destination.

25 2. In a mechanism for cutting a running web, means for successively severing it, in transit, into sheets of longer and shorter lengths and full width of the web engaged by the said severing means, and means for forwarding the cut sheets 30 of each length directly from the severing means to a different destination.

3. In a mechanism for cutting a running web, means for alternately severing it, in transit, into sheets of unequal but predetermined lengths 35 and full width of the web engaged by the said severing means, and means for separately advancing those of each length directly from the severing means to a different destination.

4. In a mechanism of the character described, 40 means for advancing a web, means for severing it in transit into longer and shorter sheets having widths equal to the full width of the web engaged by the said severing means, means for forwarding the cut sheets of each length directly from the severing means to different destinations, and means for grouping the cut sheets at said destinations.

45 5. In a web cutting mechanism, means for advancing a web, means for successively severing it in transit into longer and shorter sheets of predetermined lengths and full width of the web engaged by the said severing means, means for folding the cut sheets, and means for forwarding the sheets of each length directly from the severing means to separate folding means.

6. In a web cutting mechanism, means for advancing a web, means for successively severing it in transit into longer and shorter sheets of predetermined lengths and full width of the web engaged by the said severing means, means for longitudinally folding the cut sheets, means for selectively forwarding sheets of each length to separate folding means, and means for assembling into separate groups the sheets of each length.

7. In a mechanism of the character described, means for slitting a wide running web into a plurality of ribbons, means for advancing and juxtaposing said ribbons, means for successively severing them in transit entirely across their width into multiple sheets of unequal lengths, and means for forwarding the sheets of each length directly from the severing means to different destinations.

8. In a mechanism of the character described, means for longitudinally slitting a wide running web into a plurality of ribbons of equal width, means for advancing and juxtaposing said ribbons, means for successively severing them in transit, to form cut sheets of unequal lengths and full width of the ribbons, and means for forwarding the sheets of each length directly from the severing means to separate destinations. 5

9. In a mechanism of the character described, 10 means for slitting a wide running web into a plurality of ribbons, means for advancing and juxtaposing said ribbons, means for successively severing them in transit to provide sheets of unequal lengths and full width of the web engaged 15 by the said severing means, means for folding the cut sheets, and means for forwarding the sheets of each length directly from the severing means to a separate destination.

10. In a mechanism of the character described, 20 means for slitting a wide running web into a plurality of ribbons of uniform width, means for advancing and juxtaposing said ribbons, means for successively severing them in transit to provide sheets of unequal lengths and full width of 25 the web engaged by the said severing means, and means for selectively advancing the cut sheets of each length directly from the severing means to a separate folder and assembly mechanism.

11. In a mechanism of the character described, 30 means for forwarding a web, a pair of rotating opposed cutting cylinders adapted to receive it, cutting elements on each cylinder arranged at unequal distances apart circumferentially thereof, each adapted to co-act with a mating element 35 on the other cylinder, whereby said web is cut successively into sheets of different lengths, means adapted to forward the shorter sheets directly from the cutting cylinders to one destination and the longer ones to another destination. 40

12. In a mechanism of the character described, means for advancing and for slitting a wide web into a plurality of ribbons, means for positioning said ribbons into face to face relation and for forwarding them to a pair of synchronously rotating opposed cutting cylinders provided with a plurality of pairs of mutually registerable cutting elements spaced at unequal distances circumferentially thereof and adapted to successively cut said multiple ribbons into sheets of unequal 50 lengths, and means adapted to selectively forward the longer cut sheets directly from the cutting cylinders to one destination and the shorter ones to a different destination. 45

13. In a mechanism of the character described, 55 means for advancing and for slitting a web into a plurality of ribbons of uniform width, means for positioning said ribbons in face to face relation and for forwarding them to a pair of synchronously rotating opposed cutting cylinders provided with a plurality of pairs of mutually registerable cutting elements spaced at unequal distances apart circumferentially thereof and adapted to successively cut said multiple ribbons into sheets of unequal lengths, separate folders, means adapted to direct the longer cut sheets directly from the cutting cylinders to a folder and means adapted to direct the shorter cut sheets directly from the cutting cylinder to another folder, the folders adapted to deliver sheets 60 of each length to a separate packer box. 65

14. In a mechanism for cutting a running web, cooperating cutting cylinders, each cylinder having a cutting abutment and separate cutter-receiving recesses spaced different distances from 70 75

- the cutting abutment around the periphery of the cylinder, and a cutter secured in either cutter-receiving recess and adapted to cooperate with the cutting abutment on the opposed cylinder to cut sheets of a given length when positioned in one cutter-receiving recess and to cut sheets of a different length when positioned in another cutter-receiving recess.
15. In a mechanism for cutting a running web, cooperating cutting cylinders, a cutting abutment supported by each cylinder, and a cutter securable in two positions on each cylinder and adapted to cooperate with the cutting abutment of the opposed cylinder to cut a sheet of one length when secured in one position on the cylinder and to cooperate with the said abutment to
- cut a sheet of a different length when secured in another position on the cylinder.
16. In a mechanism for cutting a running web, cooperating cutting cylinders, each cylinder having separate cutter-receiving recesses and an abutment-receiving recess, an abutment positioned in the abutment-receiving recess of each cylinder, and a cutter positioned in a cutter-receiving recess of each cylinder and adapted to cooperate with the abutment in the opposed cylinder to cut a sheet of given length and to cooperate with the said abutment to cut a sheet of a different length when positioned in the other cutter-receiving recess of the cylinder.

15

ADOLPH M. ZUCKERMAN.
